(57) CLAIM

The ornamental design for a hair removal device, as shown and described.

DESCRIPTION

FIG. 1 is a front perspective view of a first embodiment of a hair removal device of the present invention showing our new design, the hair removal device being in a first configuration and containing movable particles;
FIG. 2 is a front view of the hair removal device;
FIG. 3 is a back view of the hair removal device;
FIG. 4 is a first side view of the hair removal device, the hair removal device being in a second configuration;
FIG. 5 is a second side view of the hair removal device, the hair removal device being rotated on its vertical axis 180 degrees relative to FIG. 4 so as to be in the first configuration and show the transitory state of the movable particles;
FIG. 6 is a further illustration of the second side view of the hair removal device showing a further transitory state of the movable particles;
FIG. 7 is still a further illustration of the second side view of the hair removal device showing a still further transitory state of the movable particles;
FIG. 8 is a top plan view of the hair removal device;
FIG. 9 is a bottom plan view of the hair removal device;

FIG. 10 is a front perspective view of a second embodiment of a hair removal device of the present invention showing our new design, the hair removal device being in a first configuration and containing color contrasted movable particles;

FIG. 11 is a front view of the hair removal device; FIG. 12 is a back view of the hair removal device; FIG. 13 is a first side view of the hair removal device, the hair removal device being in a second configuration; FIG. 14 is a second side view of the hair removal device, the hair removal device being rotated on its vertical axis 180 degrees relative to FIG. 13 so as to be in the first configuration and show the transitory state of the movable particles; FIG. 15 is a further illustration of the second side view of the hair removal device showing a further transitory state of the movable particles;

FIG. 16 is still a further illustration of the second side view of the hair removal device showing a still further transitory state of the movable particles;

FIG. 17 is a top plan view of the hair removal device; FIG. 18 is a bottom plan view of the hair removal device; FIG. 19 is a front perspective view of a third embodiment of a hair removal device of the present invention showing our new design, the hair removal device being in a first configuration and containing movable particles;

FIG. 20 is a front view of the hair removal device; FIG. 21 is a back view of the hair removal device; FIG. 22 is a first side view of the hair removal device, the hair removal device being in a second configuration; FIG. 23 is a second side view of the hair removal device, the hair removal device being rotated on its vertical axis 180 degrees relative to FIG. 22 so as to be in the first configuration and show the transitory state of the movable particles; FIG. 24 is a further illustration of the second side view of the hair removal device showing a further transitory state of the movable particles;

FIG. 25 is still a further illustration of the second side view of the hair removal device showing a still further transitory state of the movable particles;

FIG. 26 is a top plan view of the hair removal device; FIG. 27 is a bottom plan view of the hair removal device; FIG. 28 is a front perspective view of a fourth embodiment of a hair removal device of the present invention showing our new design, the hair removal device being in a first configuration and containing color contrasted movable particles;

FIG. 29 is a front view of the hair removal device; FIG. 30 is a back view of the hair removal device;

FIG. 31 is a first side view of the hair removal device, the hair removal device being in a second configuration;

FIG. 32 is a second side view of the hair removal device, the hair removal device being rotated on its vertical axis 180 degrees relative to FIG. 31 so as to be in the first configuration and show the transitory state of the movable particles; FIG. 33 is a further illustration of the second side view of the hair removal device showing a further transitory state of the movable particles;

FIG. 34 is still a further illustration of the second side view of the hair removal device showing a still further transitory state of the movable particles;

FIG. 35 is a top plan view of the hair removal device; and, FIG. 36 is a bottom plan view of the hair removal device. The subject matter in this patent includes a process or period in which movable particles change from one position into another position. This process or period forms no part of the claimed design. The broken lines shown herein illustrate portions of the hair removal device and form no part of the claimed design. The black shading shown herein represents a color contrast.
